UNITED STATES PATENT OFFICE.

ANTHONY C. BOVE, OF BROOKLYN, NEW YORK.

RADIODESK.

Application filed March 26, 1926. Serial No. 97,493.

This invention relates to combined writing desks and radio cabinets, and particularly to that type which may be used either as a writing desk or as a radio cabinet without disclosing its adaptability for use for one purpose when it is used for the other purpose.

This invention contemplates the mounting of a radio set and the operating parts thereof in such a manner that said set and parts are concealed from view when the desk is used for its normal purpose, that is, for writing. The invention further contemplates the provision of compartments normally used for holding blank stationery, letters, or other material, which may be folded out of the way when it is desired to use the radio set, and which may then be brought forward into operating position, whereby the desk is transformed into and presents the appearance of a radio cabinet.

The various objects of my invention will be clear from the description which follows and from the drawings, in which,

Fig. 1 is a perspective view of my improved desk, showing the material holding compartments at the right, in their normal or operative positions in which they are arranged when the desk is to be used as a writing desk.

Fig. 2 is a top plan view of the same partly in section.

Fig. 3 is a vertical section of the same.

Fig. 4 is a horizontal section through the top drawer, containing the loud speaker, batteries, antenna, or loop, used in connection with the radio set.

Fig. 5 is a front view partly in section of part of the radio set, showing the means for movably supporting said set, and

Fig. 6 is a vertical section taken in front of one of the pigeon holes or holding compartments and through the side of the desk, showing the means for guiding the compartment into and out of the operative position thereof.

My invention can be applied to any of the usual styles of writing desks, one type of which is indicated in the drawings and designated by the numeral 10. Said desks usually include a series of drawers 11, 12 and 13, and a hinged cover 14, which in its closed position meets the inclined edges of the sides of the desk and forms the front of said desk. Said cover 14 also serves to

conceal, and in its open position extends out to form the outer writing table.

Pigeon hole and stationery holding compartments are usually provided in desks of the type to which this invention pertains, but such compartments are usually built into place permanently at the rear of the inner writing compartment.

I prefer, however, to arrange the compartments 15, 16, 17 and 18, so that in their normal or operative positions, they extend substantially across the entire width of the inner writing table 19 in spaced relation to the removable back 20 of the desk, whereby an inner compartment or space as 21 is provided, in which a radio set as 22 is preferably centrally arranged. Said set 22 is so mounted that it may readily be moved forwardly of the inner writing table 19 when it is desired to use said set. In order that the movement of the set is not prevented by the compartments 15, 16, 17 and 18, which are normally in front of said set, and for the further purpose of allowing the concealment of said compartments from view when the set is to be used, I prefer to make said compartments movable and foldable so that they may be disposed out of the way when desired, and so that the interior of the desk may then present the appearance of a radio cabinet. Said compartments are arranged in spaced relation to the back 20 and are connected in pairs, the compartments 15 and 16 being hinged together by means of a suitable hinge as 23, and the compartments 17 and 18 being similarly hinged together by means of the hinge 24, so that each pair of said compartments may be folded together to occupy a space at the side of the radio set of about half the width of the extended compartments.

Each of the outermost compartments 15 and 18 is slidably supported by one of the sides 25 of the desk, to which is secured the guide member 26 preferably rabbeted along the lower edge as at 27. A similar guide member 28 is secured to the inner surface of each of said outer compartments, and is provided with a projecting tongue 29 operating in the groove 27 of the guide member 26, so that said compartments may be moved forwardly and rearwardly into that part of the space at the side of the radio set without allowing sidewise movement of said compartments.

2
Pigeon holes as 31 of suitable size and shape may be made in each of the compartments for holding letters, stationery or other material. In the outermost compartments 15 and 18, I prefer to provide a projecting rack as 32, which is designed to fold into and to fit into the corresponding space 33 provided in the inner compartment, to which it is secured, when said inner compartment is rotated about its hinge into the position shown at the left in Fig. 2. It will be understood, however, that the normal positions of said compartments is that shown at the right in Figs. 1 and 2, and that when the 15 inner compartment is folded upon the outer, both compartments may be moved back into that portion of the space 21 at the side of the radio set, the compartments being guided in their movement by the guide members 26 and 28 at the side of the desk.

The radio set 22 is mounted on suitable rollers 34, which operate in suitable grooves 35 formed in the inner table 19. After the compartments have been folded and pushed 25 back into their inoperative positions, the table 19 is cleared and the radio set 22 may then be pulled forward with ease until said set is in a position convenient for the manipulation of the various dials thereof. In 30 order to allow the adjacent inner compartments 16 and 17 to clear each other when moved from their operative into their folded positions, the adjacent sides 36 and 37 thereof are preferably made divergent 35 rearwardly, though it will be understood that any other suitable construction may be used if desired to prevent interference of said compartments during the folding thereof.

40 The uppermost drawer 11 is designed to hold the various accessories or operating parts of the radio set, such as the battery 38, the loud speaker 39 and the antenna or loop 40.

45 The above-mentioned parts may be separated from each other in the drawer if desired, by means of partitions as 41 and 42. If desired, suitable panels as 43 and 44 may be made at the front of the drawer for ornamental purposes at the places behind which the loud speaker and the antenna are located, the panel covering the loud speaker 39, being preferably perforated as at 44', to allow the sound from said speaker to be 50 heard effectively. The wires 46 from the loud speaker are brought up through the back of the drawer into the writing compartment, and are preferably arranged along the rear wall 20 of the desk, and along the top 55 53, whereby the jack 54 may be readily connected to a suitable plug as 55 in the radio set when it is desired to operate the loud speaker. Said wires 46 are preferably extensible, being coiled through a substantial portion of their length in order to provide

a sufficient length of wire to prevent injury thereto when the drawer 11 is pulled out or the set moved into position. Similarly, coiled wires as 47 connect the batteries to the radio set and similar wires, not shown, 70 may connect the loop 40 to the set, all of said wires being substantially entirely concealed by being passed up through the back portion of the drawer, and around to suitable connections at the back of said radio set.

In order to manipulate the antenna 40, I have provided a knob 48 on the front of the drawer 11, said knob being secured to a suitable shaft 49, at the extremity of which is mounted a bevel gear as 50. The antenna 80 or loop 40 is mounted for rotation about a vertical pivot 51 suitably secured in the drawer bottom. At the top of said pivot is mounted the bevel gear 52, meshing with the gear 50, so that rotation of the knob 48 rotates the loop 40 about a vertical axis, and the loop may be adjusted for direction.

It will be seen that the parts contained in the drawer may be readily inspected by pulling out said drawer, and that said parts 90 and the connections therefor are readily accessible through the removable back 20, and are normally entirely concealed from view. It will further be seen that the desk presents the appearance of the ordinary writing desk, but that it can be readily changed to expose the radio set and to entirely conceal the various compartments. It will further be understood that various changes are contemplated and may be made from the specific structure shown and described without departing from the spirit of this invention and the scope of the appended claims.

105 I claim:

1. In a radio desk, foldable compartments arranged normally in spaced relation to the back of said desk for providing a permanent rear space adapted to receive a radio set between the backs of said compartments and said desk back in the extended positions of said compartments and adapted to be collapsed into the end portions of said space and inside of said desk for providing an additional front central space continuous with said rear space into which the set may be moved.

110 2. In a desk, a series of compartments for holding material therein, arranged normally in spaced relation to the back of and completely across said desk, hinges connecting said compartments in pairs and allowing the folding of the compartments of a pair through an angle of 180° upon the other compartments of the pair, means on 115 the sides of the desk for slidably supporting one of the compartments of each pair whereby said compartments may be folded toward the sides of said desk in pairs about the hinge therebetween and moved back to the 120 125 130 hinge.

rear of said desk, leaving a space between the folded compartments for the reception of a radio set, and a drawer in said desk adapted to hold a loud speaker, and an antenna.

3. In a desk, a series of four compartments arranged in pairs and in spaced relation to the back of said desk, a hinge connecting the adjacent edges of said compartments whereby each of said pairs of compartments may be folded about said hinge away from the middle portion of said desk and toward the sides thereof, while being maintained at all times inside of the side walls of said desk and means on the sides of the desk for slidably supporting said compartments for movement forwardly and rearwardly of said desk whereby a space is provided between the folded pairs of compartments into which a radio set may be moved from the rear of said desk.

4. In a writing desk, pairs of compartments each hinged together and extending in the operative position thereof substantially half way across the width of said desk and cooperating means on one compartment of each pair and on the desk for supporting said pair for movement forwardly and rearwardly of said desk and for guiding said compartments in the movement thereof in all positions of said pair.

5. In a writing desk, a pair of normally aligned compartments of substantially the same width, a hinge joining said compartments, whereby one of said compartments may be folded through an angle of 180° upon the other of said compartments, thereby reducing the width of both compartments in the folded position thereof to that of a single compartment, said pair of compartments being arranged so as to remain at all times inside of said desk, means for slidably supporting one of said compartments for movement forwardly of said desk, a second pair of similar compartments spaced widthwise of the first-mentioned pair for providing a space between said pairs in the folded positions thereof.

6. In a convertible writing desk, a pair of compartments of substantially the same width arranged in spaced relation to the back of said desk, a hinge joining said compartments, whereby one of said compartments may be folded upon the other of said compartments, while remaining inside of the sides and front of the desk, thereby reducing the width of both compartments in the folded position thereof to that of a single compartment, means for slidably supporting one of said compartments of each pair for movement forwardly and rearwardly of said desk, and a radio set normally arranged behind and obstructed by said compartments and adapted to be brought forwardly of while supported by said desk

after said compartments have been folded and thereby removed from the path of said set.

7. An article of furniture convertible from a desk to a radio cabinet including a radio set arranged at the central rear portion of said article, foldable means for holding papers therein normally in spaced relation to the back of said article whereby a space is provided behind said means for said set, said foldable means being free of and independent of said set, and concealing said set and adapted to be removed from path of said set on the folding thereof inside of and adjacent to the sides of the article and means for supporting said set for movement forwardly and rearwardly of said article into the space occupied by part of said foldable means before the folding thereof.

8. In a convertible desk and radio cabinet, a writing compartment, a radio set at the central rear portion of said writing compartment, means for supporting said set for movement forwardly and rearwardly in said inner compartment and foldable compartments for holding material therein normally in spaced relation to the back of said desk, normally reaching completely across said desk for concealing said set and arranged to be folded out of the path of said set and entirely inside of and adjacent to the sides of said desk whereby said set may be moved into the additional space provided by folding said compartments of the normal positions thereof.

9. In a convertible desk and radio cabinet, an inner writing compartment in said desk, a radio set at the rear of said inner compartment, means for slidably supporting said radio set for movement in said inner writing compartment, and foldable means for holding material therein, normally concealing said radio set in the operative position thereof, and arranged to be folded out of the path of said set, and into a position entirely inside of and adjacent to the sides of the desk whereby said set may be moved into the space partly occupied by said compartments in the normal positions thereof.

10. In a radio desk, an inner writing compartment provided with a permanent rear central space adapted to receive a radio set, foldable means for holding material therein normally concealing said space and adapted to be folded into half its extended width into a space adjacent to and inside of the sides of said desk, and means for supporting said foldable means for allowing the folding of said foldable means and thereby providing a front central space into which a set may be moved from the permanent rear central space.

11. In a desk, an inner writing compartment, including an inner writing table and means for enclosing said table, a pair of

4

holders for material arranged in spaced relation to the rear of said inner writing compartment and inside of said desk and having pigeon holes therein, hinges joining said pair of holders whereby said holders may be folded together while remaining inside of said desk, with the front portions thereof in contact with each other, a guide member on the outer of said holders, and a cooperating guide member on the side of said inner writing compartment, whereby said pair of holders may be moved rearwardly and forwardly of said desk in the folded and unfolded positions thereof.

15. 12. In a desk, an inner writing compartment, including an inner writing table and means for enclosing said table, a pair of holders for material arranged normally in spaced relation to the rear of said desk having pigeon holes therein, hinges joining said pair of holders whereby said holders may be folded together with the front portions thereof in contact with each other, a guide member having a tongue projecting therefrom secured to the outer of said holders and a guide member having a groove therein adapted to receive said tongue secured to the side of said inner writing compartment.
20. 13. In a desk, more than one pair of foldable compartments normally reaching across said desk and arranged in spaced relation to and between the front and back thereof for providing a rear radio set compartment enlargable on the folding of said compartments, one compartment of each pair being mounted for the folding thereof from a rear

position near the center of said desk to a position in front of the other compartment of the pair and adjacent to a side of the desk.

14. In a desk, a holder for material having a rack projecting forwardly therefrom, a similar holder of substantially the same width having a recess therein adapted to receive said rack, hinges joining said holders foldably together, and means for supporting that one of said holders adjacent to the side of said desk to said side for movement forwardly and rearwardly of said desk.

15. In a desk, an inner writing compartment having a permanent rear central space adapted to receive a radio set, holders arranged at all times in said compartment and normally in aligned extended position for concealing said space, and hinges joining the adjacent edges of said holders in pairs whereby one of the holders of each pair may be swung about the hinges into a position forwardly of the other holder of the pair while remaining inside of said compartment for providing access to and from said permanent space.

16. In a desk having an inner writing compartment having a permanent rear unobstructed space adapted to receive a radio set, and foldable means arranged completely across said compartment for normally concealing said permanent space and for providing an additional space into which said set may be moved on the folding thereof, said means being maintained within said compartment in all positions thereof.

ANTHONY C. BOVE.
